TOY VEHICLE WHEEL

Harry Golden, New York, N.Y., assignor to Ideas for
Auto and Bike Specialties, Inc., New York, N.Y.

Filed Mar. 9, 1970, Ser. No. 21,779

Term of patent 14 years

Int. Cl. D21—02

U.S. Cl. D34—15

FIG. 1

FIG. 2

FIG. 3

FIG. 4

FIG. 1 is a front elevational view of a toy vehicle wheel, showing my new design;

FIG. 2 is a side elevational view thereof;

FIG. 3 is a rear elevational view thereof; and

FIG. 4 is a fragmentary sectional view thereof taken along the line 4—4 of FIG. 3.

I claim:

The ornamental design for a toy vehicle wheel, as shown and described.
